CLAIM

I claim the ornamental design for a base for supporting a piece of hardware, as shown and described.

DESCRIPTION

FIG. 1 is a perspective front view of the base for supporting a piece of hardware, such as a card processing terminal or the like, showing my new design;

FIG. 2 is a left side view thereof;

FIG. 3 is a right side view thereof;

FIG. 4 is a front view thereof;

FIG. 5 is a back view thereof;

FIG. 6 is top view thereof; and,

FIG. 7 is a bottom view thereof.
